FREQUENCY REDUCTION DEVICE

Kurt Schlesinger, Berlin, Germany, assignor, by
mesne assignments, to Loewe Radio, Inc., a cor-
poration of New York

Application July 23, 1936, Serial No. 92,153
In Germany July 27, 1935

1 Claim. (Cl. 250—36)

The problem of producing a frequency which is an integral fraction of a control frequency often arises in the electrical oscillation art, for example in radio telephony and in television.

5 Frequency dividers using electron tubes are well known. This invention relates to frequency dividers of this kind, and its object is a frequency reduction devise of highest reliability.

10 Another object of this invention is to synchronize the lower frequency f_a by the higher control frequency f_{st} without retroaction.

Another object of this invention consists in obtaining the lower frequency in the form of short synchronizing impulses.

15 In the drawing,

Fig. 1 is a schematic diagram of a connection according to this invention, and

Fig. 2 are curves illustrating the functions of the device of Fig. 1.

20 The principle of this invention consists in controlling the frequency f_a of an ordinary oscillation generator by means of an additional grid connected to the higher frequency source. Consequently a tube having two or more grids 25 is used. Admirably suited for this purpose are normal pentodes having a screen grid and a suppressor grid which are provided with external terminals.

30 In Fig. 1 the pentode contains a cathode 1, a control grid 2, a screen grid 3 with positive bias, a suppressor grid 4 and an anode 5. The screen grid 3 is connected as usual with approximately half the anode battery potential, which is adjusted by means of a potential distributor 6, 7 and is earthed by means of a condenser 8. The bias of grid 4 is adjusted by means of battery 13 in series with resistance 12 and 21. The reaction coupling between the grid coil 9 and the oscillatory circuit 10/11 takes place by any of the usual methods, for example inductively. 35 Oscillations of the frequency f_a in the anode circuit 10/11 are generated so long as the distributor grid 4 permits the passage of current to the anode.

40 According to the invention, there is applied to the distributor grid 4 by way of a condenser 14 the control potential 15, the frequency of which f_{st} is assumed to be an integral multiple of the frequency f_a .

45 In Fig. 2 there is shown the form of the anode current. If the suppressor grid 4 were permanently connected for transmission, for example permanently connected with the cathode, there would result in the tube an oscillation of the frequency f_a . The form of the grid alternating

5 potential of the grid 2 controlling this oscillation in the tube is represented in Fig. 2 by the curve 16. The potential prevailing at the suppressor grid 4 has a harmonic frequency of 16, for example double frequency. The same is shown in the curve 17. From the co-operation between both oscillations the anode current which occurs may be derived as follows:

10 In the first half-cycle of 17, which is designated a , the suppressor grid is supplied with a 10 potential permitting current to flow through the tube. There accordingly occurs in this phase an anode current which is designated 18. In the second half-cycle of the suppressor grid potential 17, which is designated b , anode current 15 is no longer able to flow, as in this half-cycle the suppressor grid potential is negative. The anode current, therefore, in this range is "zero." In the third and fourth half-cycles of the control 20 regions designated by c and d , however, the anode current is in any case "zero," because in this range the control grid 2 is negative. Consequently, for each two full cycles of the control frequency f_{st} there is produced merely one 25 single current impulse at the anode 18. 25

In addition to this frequency reducing effect there also occurs a synchronizing effect. It will be clear from the above remarks that the oscillation f_a of the circuit 10/11 is only generated if its frequency is subharmonic to the control 30 frequency f_{st} , as otherwise the periods in which the tube would be traversed by current would not coincide with the transmission periods of the suppressor grid 4.

The frequency of the useful oscillation f_a thus 35 generated is accordingly distinctly determined by the control frequency f_{st} . It depends on the tuning of the circuit 10/11 merely insofar as with a detuning of f_a taken too far in relation to $1/n$, 40 f_{st} is concerned.

The curvature of the potential furnished by the generator is a nearly pure sinusoidal one when taken by coupling to the coil 10.

45 In many cases, however, there is the desire for a potential, the form of which coincides with the time curve 18 of the anode current. At the same time there should also be adjustable as far as possible the duration time T of the anode current impulse or of this useful potential. A coupling of this nature may be realized by the introduction of an ohmic coupling resistance 19 in the anode circuit. The resistance 19 should be small compared with the inner resistance of the tube. In the case of pentodes 19 may readily be made to be 10,000-30,000 ohms or more. The potential 50 55

tapped at 19, possibly by way of a coupling condenser 20, then supplies the impulse indicated by 18 in Fig. 2. The strength of the impulses may be adjusted by varying the resistance 19. The duration time T of the impulses, in accordance with the invention, may be varied by varying the bias 13 of the suppressor grid 4, generator 15 remaining at constant potential, or vice versa by varying the amplitude of 15 only. Certainly 10 the first method is better, as in this case the generator 15 limiting methods known per se (grid current limitation and anode current limitation of the terminal tube) may be provided which represent effective means against interfering 15 ripple, hum modulation, etc. It will be obvious that in the case of a more negative bias 13 the duration of the transmission phase of 4 becomes shorter and shorter, and the impulse duration time T is accordingly reduced. The greatest 20 duration which time T is capable of attaining is the full half-cycle of the control frequency f_{st} .

If very short impulses are to be generated, there are two possibilities. In the one case the negative bias 13 is increased more and more until 25 merely the extreme positive peak values of the potential variations from generator 15 impulse the suppressor grid. In this connection there is reached a limit of accuracy, as small fluctuations in the amplitude of 15 already lead to considerable 30 variations in the impulse duration owing to the weak intersection low rate of change of the curve. The second method of obtaining still shorter impulses without encountering these difficulties as regards amplitude consists in selecting 35 as the control frequency a higher harmonic of the useful or desirable frequency, i. e., not the double but the triple or quadruple harmonic. The longest impulse duration is then merely a fraction of the longest duration time T just considered, and the range of still shorter impulse 40 signals is reached without difficulty.

It may be especially pointed out that in the above there are described particular forms of

embodiment of the general idea according to the invention, and that modifications may be made in the present invention without departing from the spirit and scope thereof.

I claim:

A circuit for producing unidirectional impulses at a predetermined rate and of a predetermined duration comprising, an electron discharge tube having a cathode, a first control electrode, a second control electrode and an output electrode, 10 means including an inductance for normally maintaining said first control electrode negative with respect to said cathode, a tuned circuit comprising a parallel connected condenser and inductance, means for connecting one terminal of 15 the tuned circuit to the output electrode of said tube, means including a load resistance for maintaining the other terminal of the tuned circuit positive with respect to the cathode, said first-named inductance and the inductance of said 20 tuned circuit being mutually coupled, an output circuit coupled across the cathode and the junction of the load resistance and the tuned circuit, means including a resistance for normally maintaining said second control electrode negative 25 with respect to the cathode, said negative potentials being of such magnitude as to substantially block the tube, means for applying voltage variations of a fixed frequency between the second control electrode and the cathode, the resonant 30 frequency of the tuned circuit being approximately one-half the frequency of the voltage variations applied to said second control electrode, said applied voltage variations and the voltage produced by said mutual coupling having such 35 amplitude that said tube is unblocked only when said applied voltage and said produced voltage are each positive, whereby unidirectional impulses of a rate substantially coinciding with the frequency of the tuned circuit and having a duration corresponding to approximately one-fourth 40 the time occupied by one cycle at said frequency are present in said output circuit.
